GROUND PAD

Martin N. Haller, Pittsburgh, Pa., assignor to the United States of America as represented by the Secretary of the Army

Application August 3, 1953, Serial No. 26,459

Term of patent 14 years

(Cl. D5—2)

To all whom it may concern:

Be it known that I, Martin N. Haller, a citizen of the United States of America, residing at Pittsburgh, Pennsylvania, have invented a new, original, and ornamental Design for a Ground Pad, of which the following is a specification, reference being had to the accompanying drawings, forming a part hereof.

Fig. 1 is a top plan view of a ground pad embodying my new design;

Fig. 2 is a side elevation of the same;

Fig. 3 is an end elevation of the same; and

Fig. 4 is an enlarged perspective view of one of the resilient blocks forming a part of the ground pad, shown attached to a fabric backing.

The bottom surface of the ground pad is not shown because it is substantially plain.

I claim:

The ornamental design for a ground pad, as shown and described.
